[57] **CLAIM**

The ornamental design for a baseball equipment holder,
as shown and described.

DESCRIPTION

FIG. 1 is a top front, and left side perspective view of a baseball equipment holder showing my new design;
FIG. 2 is an enlarged front elevational view thereof;
FIG. 3 is an enlarged right side elevational view thereof, the left side being a mirror image of that shown;
FIG. 4 is an enlarged top plan view thereof; and
FIG. 5 is an enlarged bottom plan view thereof.
The rear elevation view is flat and unornamented.

FIG. 1.

FIG. 4.

FIG. 5.

FIG. 3.

FIG. 2.
